(57) **CLAIM**

We claim the ornamental design for a handle interface, as shown and described in the figures.

DESCRIPTION

FIG. 1 is a perspective view of a handle interface embodying the invention.

FIG. 2 is a left side view of the handle interface shown in FIG. 1.

FIG. 3 is a right side view of the handle interface shown in FIG. 1.

FIG. 4 is a front view of the handle interface shown in FIG. 1.

FIG. 5 is a rear view of the handle interface shown in FIG. 1; and,

FIG. 6 is a top view of the handle interface shown in FIG. 1.

The portions of the handle interface shown in broken lines are included for the purpose of illustrating environment and form no part of the claimed design.
